UNITED STATES PATENT OFFICE

EARLE R. FAIREY, OF HAMILTON, ONTARIO, CANADA

CALENDAR

Application filed July 15, 1929. Serial No. 378,312.

This invention relates to portable calendars and has special reference to portable calendars adapted to be carried in the pocket as is a watch or to be worn in a manner in which a 5 wrist watch is worn.

One important object of the present invention is to improve the general construction of such calendars.

A second important object of the present 10 invention is to provide an improved gearing arrangement for calendars of this description.

A third important object of the invention 15 is to provide an improved form of portable annual calendar wherein arrangement is made for substituting one calendar strip for another by simple means requiring no tools.

A fourth important object of the invention 20 is to provide a calendar of this description having winding means movable into and out of operating position so that when in one position the calendar strip may be shifted and when in another position the winding means 25 will be detached so that the calendar strip cannot be readily moved.

With the above and other objects in view as will be hereinafter apparent, the invention 30 consists in general of certain novel details of construction and combinations of parts 35 hereinafter fully described, illustrated in the accompanying drawings and specifically claimed.

In the accompanying drawings like characters of reference indicate like parts in the 35 several views, and:

Figure 1 is a face view of one form of the invention adapted for use as a pocket watch.

Figure 2 is a face view of a second form of 40 the invention adapted for use as a wrist watch.

Figure 3 is an enlarged detail section taken on the longitudinal median plane of the device.

Figure 4 is a detail section partly broken 45 away on the line 4—4 of Figure 3.

Figure 5 is an edge view of the form of the invention shown in Figure 2.

Figure 6 is a view showing one end of the 50 calendar strip.

Figure 7 is a view showing the other end of said strip.

Figure 8 is a detail view showing the arrangement of the movable operating means for the calendar.

In the embodiment of the invention herein illustrated there is provided in each form a casing 10 having a back wall 11 and on the front of this casing is provided a suitable opening surrounded by a bezel 12 wherein 60 is fitted a glass panel or lens 13. Extending between the side walls 14 of the casing just below the lens or crystal 13 is a guide plate 15. Adjacent each end of the casing is a shaft 16 which is provided with a slot 17 ex- 65 tending longitudinally thereof for the reception of the tapered ends 18 of a calendar strip formed of any suitable material such as silk and cotton tape and provided with a series of monthly calendar indications 19 printed 70 thereon. These monthly calendars may be of any desired number or arrangement. For instance, the twelve months of one year may be shown or twelve months of one year with an additional two months of the next year 75 or six months of one year and six or eight of the months of the next year. In fact, any desired arrangement may be used. This strip runs from one of the shafts or rollers 16 over the plate 15 to lie close below the crystal 13 80 for ready observation. Centrally of the casing is a winding shaft 20 carrying a winding knob 21 slidably mounted on the shaft so that in one position a small projection 22 drops into a recess 23 in the sleeve 24 carrying 85 the winding knob while in a second position this small projection drops into a groove 25 also formed in this sleeve. Obviously, in the first position the sleeve and shaft will revolve together while in the second position 90 the sleeve is free to revolve on the shaft. On each shaft 16 is a pair of gears 26 and on the shaft 20 is a pair of gears 27 and idler gears 28 are arranged between the gears 27 and the gears 26 as shown in Figure 4. By means 95 of this arrangement the calendar may be moved to bring the required month beneath the crystal and when exhausted the strip may be removed by simply pulling out the ends from the slots and a new strip substituted. 100

it being understood that the back, preferably, of the casing is so arranged like the back of an ordinary watch, that it may be opened for access to the interior. The casing may either 5 be of the form shown in Figure 1 or may, as in Figure 2, be provided with loops 29 for the reception of a wrist strap 30 and obviously the calendar may be used either alone on the wrist of the wearer or a watch may 10 be worn on one side of the wrist and the calendar on the other, a single strap 30 serving to hold the two in position.

There has thus been provided a simple and efficient device of the kind described and for 15 the purpose specified.

It is obvious that minor changes may be made in the form and construction of the invention without departing from the material spirit thereof. It is not, therefore, desired 20 to confine the invention to the exact form herein shown and described; but it is desired to include all such as properly come within the scope claimed.

Having thus described the invention, what 25 is claimed as new, is:

In a portable calendar, a casing, a pair of winding shafts at opposite ends of said casing, gears on said shafts, a driving gear, a winding stem carrying said driving gear, 30 idler gears connecting the driving gear with the first mentioned gear, a winding knob on said stem, said knob having longitudinal sliding connection with said stem and arranged in one position to drive the stem and in a second position to rotate freely thereon, said 35 shafts each having a longitudinal slot therein, and a calendar tape having calendar indicia thereon and provided with tapered ends engaged in said slots.

In testimony whereof he has affixed his signature.

EARLE R. FAIREY.
